UNITED STATES PATENT OFFICE.

ELWOOD T. LARKIN, OF BUFFALO, NEW YORK, ASSIGNOR TO CHARLES A. CRIQUI, OF BUFFALO, NEW YORK.

INTERNAL-COMBUSTION ENGINE WITH ROTARY VALVE.

Application filed February 17, 1926. Serial No. 88,818.

This invention relates to internal combustion engines of the kind having removable cylinder heads, and more particularly to engines of this kind having rotary valves.

5 The objects of this invention are to construct a multi-cylinder engine of this kind in which rotary valves are used in connection with cylinder heads which are removable individually; also to provide an improved arrangement of a cylinder head and a rotary valve in a cylinder member or casting of an internal combustion engine to facilitate the manufacture and assembling thereof and to improve the cooling of the valve; also to 10 provide means of improved construction for holding the cylinder heads and valves in correct relation to the cylinder member or casting of the engine; also to improve the construction of engines of this kind in other respects hereinafter specified.

In the accompanying drawings,

Fig. 1 is a fragmentary, transverse, sectional elevation of the upper portion of an internal combustion engine, showing the removable cylinder head and valve, the section being taken on line 1—1, Fig. 2.

Fig. 2 is a fragmentary, top plan view thereof, partly in section, on line 2—2, Fig. 3.

Fig. 3 is a fragmentary, elevation thereof, partly in section, on line 3—3, Fig. 2.

Figs. 4 and 5 are enlarged, fragmentary, sectional elevations thereof on lines 4—4 and 5—5, respectively, Fig. 2.

35 The engine to which my invention is applied may have any desired number of cylinders 10 in which pistons 11 may reciprocate, the cylinders being cooled by jackets 12 through which water or other cooling liquid may circulate and which may be formed around the cylinders in any usual or suitable manner. The cylinders 10 and water jackets 12 preferably form a part of a cylinder member or casting which is also provided with an 45 integral upwardly extending portion formed with cylinder head chambers which are of cylindrical bore and preferably formed concentric with the cylinder above the same and of slightly larger diameters than the cylinders, thus forming shoulders 14 at the upper 50 ends of the cylinders and at the lower ends of cylindrical walls 15 of the cylinder head chambers. The upper part of the cylinder member, in the particular construction illustrated, is provided at one side with a plural-

ity of inlet passages 16, one being provided for each adjacent pair of cylinders as indicated in the right hand side of Fig. 2. These inlet passages connect with an inlet manifold 17 which may be suitably secured on the engine cylinder member. Preferably at the opposite side of the cylinder member exhaust passages 18 are provided, each of which also serves two adjacent cylinders and these passages are connected with an exhaust manifold 19. Both the inlet and exhaust passages in the cylinder member terminate in the cylinder head chambers, and each of these passages of the cylinder member is divided into two passages leading to two adjacent cylinders by means of an upright jacked portion 20 of the engine cylinder member, which also forms a part of the wall of the two adjacent head chambers.

The individually removable cylinder heads which are adapted to be located in the cylinder head chambers of the cylinder member include an outer substantially cylindrical wall 22 terminating at its lower ends in an outwardly extending radial flange 23, the lower edge of which is adapted to seat upon a shoulder 14, a gasket 24 being preferably inserted between the shoulder and the outwardly extending flange of the cylinder head as shown in Fig. 5, and a rotary or sleeve 25 is positioned in the space between the cylinder head wall 22 and the walls 15 of the head chambers, the lower end of the sleeve bearing on or extending into close proximity to the upper face of the annular flange 23 of the cylinder head. The flange 23, in addition to forming a tight joint with the shoulder 14 also serves to center the cylinder head in the cylinder head chamber so that the cylinder head wall 22 will be truly 90 concentric with the chamber wall 15.

Each cylinder head is provided with an upwardly extending cavity 27 in the bottom thereof which is substantially conical in form and forms a combustion chamber. This 100 cavity 27 is connected by means of two passages 28 and 29 respectively with the inlet and exhaust passages 16 and 18 of the cylinder member, through the medium of ports in the rotary or sleeve valve.

In the particular construction shown the rotary valve is in the form of a hollow open ended cylinder provided in its cylindrical wall with two ports 30 and 31 which are so arranged as to establish and break commun- 110

cation between the inlet passages 16 and 28 and the exhaust passages 18 and 29, at the proper time. The rotating of these valves may be effected in any suitable or desired manner. In the particular construction shown each of these valves is provided near its upper portion with an outwardly extending flange 33 on which worm gear or spiral gear teeth 34 are formed, which teeth are adapted to mesh with worms or spiral gears 35 secured on a shaft 36 which is suitably journalled on the upper part of the cylinder member of the engine. The cylinder head chamber is provided with a corresponding portion 37 of larger bore which is adapted to accommodate the flange 33 and teeth 34 of the valve. Any other means for driving the rotary valves may, of course, be employed, if desired.

20 The arrangement of the cylinder head and valve in the head chamber of the engine greatly facilitates machining and assembling of this portion of the engine, since the valve 25 telescopes over the head, and the valve 25 and head can then together be inserted into the head chamber. The adjacent or engaging cylindrical surfaces of the valve, head and head chamber can easily be machined to produce an accurate fit.

30 In order to clamp the cylinder head in its head chamber in the cylinder member and at the same time to center the upper portion of the cylinder head relatively to the head chamber and confine the rotary valve in its operative position, a clamping and centering ring 40 is preferably employed, which ring is made to fit snugly within the counter bored portion 37 of the cylinder head chamber, and has a downwardly extending annular shouldered portion or flange 41 which extends into the space between the upper edge of the cylinder head and the head chamber. This flange accurately spaces the upper end of the cylinder head relatively to the head chamber, and in conjunction with the spacing flange 23, ensures a truly concentric space between the cylinder head and head chamber in which the rotary valve is located. The flange 41 extends into close proximity to the upper end of the rotary valve 25, and confines the same in its operative position. The clamping rings may be clamped downwardly into their operative position in any suitable or desired manner. In the particular construction shown, a plurality of clamping bars 42 are provided, each of which is arranged to engage two adjacent clamping rings 40 and these bars 42 are adapted to cooperate with studs 43 secured on the cylinder member of the engine, for example, the bars 42 may have central apertures through which the studs 43 extend, and nuts 44 may be employed for drawing the clamping bars 42 downwardly against the clamping rings 40, which in turn are pressed downwardly

against the cylinder heads to force the annular flanges 23 thereof into engagement with the gaskets 24. By means of this construction the studs 43 can be made of relatively large size, since each stud acts on two different cylinder heads, and these large studs are much less apt to be damaged during the shipment or handling of the engine than are the smaller studs heretofore commonly used. Other means for securing the cylinder heads in their chambers may, however, be employed, if desired.

35 The ignition of the explosive mixture in the combustion chamber 27 of the cylinder head may be effected in any suitable or desired manner. In the construction shown a pair of spark plugs 45 are provided for this purpose which are secured in downwardly extending depressions 46 in the cylinder heads and which extend into the passages 28 and 29 of the cylinder heads, which passages terminate in the combustion chamber 27.

40 The cylinder heads of the engine are cooled by means of cooling liquid circulated in spaces 48 in the heads, these circulating spaces being arranged between the walls of the combustion chamber and inlet and exhaust passages 28 and 29, an upper wall 49 of each cylinder head, and the cylindrical side walls 22.

45 The means for circulating cooling liquid in the cylinder heads is preferably substantially the same as described in my copending application No. 88,819, and includes a siphon tube 50 of substantially inverted U-shape for each cylinder head. One of the arms of the inverted U-shaped siphon tube 50 is longer than the other, and the longer arm extends downwardly through the water jacket surrounding the cylinder head chamber at the upper portion of the cylinder member, and the lower end thereof extends into a supply passage 51 extending lengthwise of the engine. The supply passage in the particular construction shown is formed integral with the cylinder member and receives the water or other cooling liquid from the usual circulating pump or the like (not shown) through a pipe 52. The shorter arm of the siphon tube extends downwardly into the cooling liquid space of a cylinder head into close proximity to the bottom thereof, so that the coldest liquid will be discharged into contact with the lower wall and combustion chamber wall of the cylinder head which are subjected to the greatest heat. The cooling liquid is discharged from each cylinder head into the upper portion of the jacket surrounding the cylinder head chamber by any suitable means such for example as a short inverted U-shape pipe 54, one end of which terminates at the upper end of a cylinder head as clearly shown in Fig. 4 and the other end of which terminates in the upper part of the water space of the cylinder member. Any suitable or de-

sired means for forming water tight joints between the tubes 50 and 54 and the jacketed portions of the cylinder heads and cylinder member may be employed, such for example 5 as threaded nipples 55 suitably secured to the jacketed portions of the cylinder heads and cylinder member and cooperating with gland packing nuts 56 of usual construction. The tube 50 is preferably made of a single piece 10 and extends through the nipples 55 in the cylinder head and cylinder member, but, if desired, the tube may be made of more than one piece, the unitary construction being preferable to prevent any air leak from interrupting the siphon action which takes 15 place when the water is drained from the cylinder jackets of the engine since the longer leg of the inverted U-shape tube 50 terminating in the water supply passage 51 will cause 20 water to flow in this tube by the siphon principle and thus withdraw most of the water from the cylinder head to which the siphon tube is connected.

By means of the construction described 25 the several parts of the engine, such as the heads, the rotary valves, and the head chambers in the cylinder member can be very readily machined and assembled. The inner cylindrical face of the walls 15 of the cylinder head chambers can be easily bored to 30 the correct diameter, and the valves and the cylinder heads can be machined separately so that they can be easily handled. When the engine is being assembled or taken down, 35 each cylinder head can be removed independently of any other cylinder head, and even in comparatively large engines these cylinder heads can be handled without the use of hoisting apparatus or devices. The 40 machining of the cylinder heads is greatly facilitated since practically only the outer cylindrical surfaces of the cylinder heads and the bottom and top edge portions thereof need to be machined with accuracy. The 45 making of the cylinder heads and individual units also facilitates the casting of the same and makes it possible to make the cylinder heads of different material from the cylinder member.

50 The rotary valves in the construction described are thoroughly well protected against the high temperatures of the engine since all parts of these valves with the exception of those closing the inlet and exhaust 55 passages are arranged between the jacketed or cooled walls of the cylinder heads and the cylinder member.

I claim as my invention:

1. An internal combustion engine including a cylinder member having a cylinder and a cylinder head chamber arranged in alignment with the cylinder and of greater diameter to form a shoulder at the juncture of said cylinder and chamber, a cylinder head 60 removably secured in said chamber and hav-

ing an outwardly extending flange adapted to seat on said shoulder to form a tight joint therewith, and a rotary sleeve valve rotatably arranged about said head and bearing at its lower end on said outwardly extending flange. 70

2. An internal combustion engine including a cylinder member having a cylinder and a cylinder head chamber formed therein, a cylinder head removably secured to said head chamber and having an outwardly extending flange engaging said head chamber to center said cylinder head therein, a rotary valve arranged about said head above said flange, and a ring detachably secured 75 to the cylinder head and engaging said head chamber for centering the upper end of said head relatively to said head chamber. 80

3. An internal combustion engine including a cylinder member having a cylinder and a cylinder head chamber formed therein, a cylinder head removably secured to said head chamber and having an outwardly extending flange engaging said head chamber to center said cylinder head therein to form 85 an annular space between said head and said head chamber, a rotary valve arranged in said annular space, and a member at the upper end of each cylinder head and detachable from said head and head chamber 90 and adapted to close said space and to center the upper portion of said head in said head chamber. 95

4. An internal combustion engine including a cylinder member having a cylinder and a cylinder head chamber formed therein, a cylinder head removably secured to said head chamber and having an outwardly extending flange engaging said head chamber to center said cylinder head therein to 100 form an annular space between said head and said head chamber, a rotary valve arranged in said annular space, a centering ring engaging the upper portion of said cylinder head and entering into said space 105 to close said space and to center the upper portion of said head in said head chamber, and clamping means for securing said centering ring in its operative position and for holding said head in said head chamber. 110

5. An internal combustion engine including a cylinder member having a cylinder head chamber formed therein, a cylinder head removably arranged in said chamber and having portions thereof spaced from said chamber walls, means for centering the lower end of said cylinder head in said head chamber, a rotary valve arranged in the space between said cylinder head and said head chamber, and a centering member engaging the upper 125 end of said cylinder head and entering into said head chamber, said member having a part entering into the space between said head chamber and the upper part of said cylinder head to center the upper part of 130

said cylinder head relatively to said chamber, and clamping means for securing said head in said chamber.

6. A multi-cylinder internal combustion engine including a cylinder member having cylinders and cylinder head chambers formed therein, individual cylinder heads removably secured in each of said head chambers, rotary valves arranged between said cylinder heads and head chambers, centering rings engaging said cylinder heads and head chambers to center the upper portions of said cylinder heads in said head chambers, clamping bars engaging adjacent pairs of centering rings, and a single clamping device for securing each clamping bar in a position to clamp said centering rings and cylinder heads in their operative positions.

7. In an internal combustion engine including a cylinder member having a cylinder head chamber formed therein, the combination of a cylinder head arranged in said head chamber, a rotary valve arranged between said cylinder head and said head chamber, spaces in said cylinder head and in said cylinder member surrounding said head chamber for the circulation of cooling liquid, a supply passage on said cylinder member for supplying cooling liquid, and a siphon tube of substantially inverted U-shape having a longer part which extends into said supply passage and receives liquid therefrom and a shorter part which extends into said cylinder head near the bottom of

the cooling liquid space therein and straddling a part of said rotary valve, whereby when water is withdrawn from said supply passage, the water from the cylinder head will be withdrawn through said siphon tube by a siphon action in a direction reverse from that in which the liquid flows during the operation of the engine.

8. In an internal combustion engine having a jacketed cylinder member provided with an integral cylinder head chamber at an end thereof, the combination of a cylinder head arranged in said head chamber, a rotary valve arranged between said cylinder head and said head chamber, spaces in said cylinder head for the circulation of cooling liquid, a supply passage on said cylinder member through which cooling liquid is supplied to the engine, a siphon tube of substantially inverted U-shape having a longer part which extends into said supply passage and a shorter part which extends into said cylinder head near the bottom of the cooling liquid space therein, whereby, when water is withdrawn from said supply passage, the water in the cylinder head will be withdrawn to the supply passage by a siphon action, and conduits connecting the upper part of the liquid space in said cylinder head with the jacketed part of the cylinder member, whereby cooling liquid is first used in the cylinder head and then in the engine jackets.

ELWOOD T. LARKIN.
